UNITED STATES PATENT OFFICE.

JOHN M. GRIEST, OF CHICAGO, ILLINOIS, ASSIGNOR TO THE SINGER MANUFACTURING COMPANY OF NEW JERSEY.

TUCK CREEASING OR MARKING ATTACHMENT FOR SEWING-MACHINES.

SPECIFICATION forming part of Letters Patent No. 394,971, dated December 25, 1888.

Application filed December 27, 1887. Serial No. 259,096. (No model.)

To all whom it may concern:

Be it known that I, JOHN M. GRIEST, a citizen of the United States, residing at Chicago, in the county of Cook and State of Illinois, 5 have invented certain new and useful Improvements in Tuck Creasers or Markers for Sewing-Machines, of which the following is a specification, reference being had therein to the accompanying drawings.

10 My invention relates more particularly to that class of tuck creasing or marking devices in which the creasing is effected by a small grooved roller having an intermittent yielding contact with an upturned lip on the base- 15 plate or lower arm of the attachment and operated from the needle-bar of the machine, so as to be moved back and forth over the said lip, between which and the said roller the work to be creased is fed.

20 The object of my invention is to provide a simple, compact, and strong creasing or marking device of the class referred to, which will operate in a silent and positive manner; which may be thrown out of operation, when de- 25 sired, without removing it from the machine, and which is adapted to crease the goods nearer to the line of stitches than the devices now generally in use.

In the drawings, Figure 1 is a partial front 30 view of a sewing-machine with my marker in operative position relative to the presser and needle bars thereof. Fig. 2 is a front view of the marker. Fig. 3 is a cross-section of the same on line 3 3, Fig. 2; and Figs. 4 and 5 are 35 vertical and horizontal sections through the supporting-bracket. Fig. 6 is a detail front end view of the marker. Fig. 7 is an enlarged detail view of the retaining bar or block.

A denotes a portion of the depending "head" 40 at the forward end of the bracket-arm of a sewing-machine, B the needle-bar, and C the presser-bar. Surrounding the presser-bar, which is, as usual, arranged rearward of the needle-bar, is a tubular attachment-holding 45 bar, D, such as is fully described in my application Serial No. 259,089, filed simultaneously herewith, the attachment-bar being provided with a clamping-lever, d, operating as set forth in my said application.

50 E denotes the frame or body bar of the at-

achment, said bar being bent downward to form a lower flattened portion, e, provided at its forward end with a knife-edge or upturned creasing-lip, e', which is preferably directly below the forward end of the bar E.

F is a bracket having backwardly-turned 55 perforated ears f, through which the rod E passes, the said bracket serving to secure the creaser to the attachment-bar D.

G is a rocking marker-carrying bar or shaft 60 extending lengthwise of the marker and journaled on the bar E, and retained thereon by the screw e², the said bar G having depending arms g and g'. The creasing-wheel g² is arranged in a recess in the lower end of the arm 65 g, and is journaled on the spring-rod h, attached at its rear end to the arm g' of the rocking-bar G. The arm g, through which the forward or free end of the spring-rod h passes, is provided with a slot, g³, to permit 70 of a limited vertical movement of the said end of the said rod, so that the creasing-wheel, which is normally pressed down against the lip e' by the spring-rod h, will have a yielding pressure against said lip, as is de- 75 sirable in this class of devices.

The rocking bar G is operated positively in both directions by a forked lever, which engages a screw or projection on the machine needle-bar, and which is preferably made in 80 two separable portions, i and i', the part i having a notched portion, i², to embrace the said rocking bar. One or both parts of this operating-lever are of spring metal and are held together by a pin, i³, on the part i, said 85 pin entering a hole or slot in the part i', which springs over the said pin. By a slight lateral pressure the operator can disengage the part i' from the pin i³, and the two arms or parts of the said lever will then be free to be separated, as indicated by dotted lines, Fig. 3, and the creaser can thus be thrown out of operation without removing it from the machine, the needle-bar screw or projection moving freely up and down without engagement with 90 the operating-lever when the two parts of the latter are thus separated.

J is a gage or edge-guide carried by a bent rod or wire, j, which passes through the ears f of the bracket F and is adjustable through 100

the said bracket. The supporting-bar E is also adjustable through the bracket F, so as to vary the position of the creasing-wheel g^2 and lip e' relative to the needle in forming 5 marks or creases for tucks of different widths, the said bar E and the guide-carrying rod j being both secured in place by a retaining-loop, K, having a threaded stem to receive a set-nut, L. The loop K embraces the bar E 10 and rod j , as shown in Fig. 4, and also a retaining-block, m, interposed between the said bar and rod. To prevent turning or lateral displacement of the said loop, its forward end is entered into a slot or recess, f' , in the 15 bracket F, and to form a neat finish for this part of the device the said loop and the block m are incased by a cap or housing plate, n. The bar E and the rod j are both provided with flattened faces, which are in contact with 20 the block m, (see Fig. 4,) and which prevent these parts from rocking and thus getting out of place.

When the set-nut L is loosened, the bar E and rod j will be free to be adjusted laterally 25 through the ears of the bracket F; but when the said nut is tightened against the housing-plate n the loop K will draw the rod j against the block m, forcing the latter against the bar E and causing said bar to impinge against 30 the ears f of the bracket F, and thereby securing or holding all of these parts in place. The block m is provided at both ends with small shoulders m' , (see Fig. 7,) which abut against the ears f of the bracket F to prevent 35 displacement of the said block, the latter having also a notch, m^2 , to receive the parts i and i' of the forked operating-lever, said notch thus serving to hold the two parts of the said lever in contact with each other, 40 and also to retain the said lever in proper position contiguous to the bracket F, so that it will not be accidentally displaced when the bar E or rod j are adjusted through said bracket or at other times. The block m also 45 serves to separate the bar E and rod j , so that either of these parts may be adjusted without accidental displacement of the other, such as might occur if these two parts were in frictional contact. The operating-lever is also 50 provided with a curved slot, i' , which receives the rod j , and also the thin portion of the block m, opposite the notch m^2 , the said rod or block serving as a stop against which the upper end wall of the said slot may abut to 55 prevent the part i' of the operating-lever from falling down onto the work when the two arms or parts of the said lever are separated to throw the creaser out of operation without removing it from the machine.

60 From the foregoing it will be apparent that when the creaser or marker is secured in operative position on a sewing-machine and the machine set in motion the rocking bar or shaft G will be vibrated from the operating-lever, which receives its movements from the needle-bar of the machine to cause the creasing-roller carried by the said rocking bar to

come in contact with and to move back and forth over the fabric resting on the knife edge or lip e' , the creasing-roller moving from 70 the position shown in full lines to that shown by dotted lines, Fig. 6, and back again at each stroke of the needle-bar, the said roller being lifted from the fabric when the needle is out of the work and the latter is moved forward by the feed, thus leaving the work unimpeded by the pressure of the creaser during the times of the feeding movements.

It will be observed that the creasing-roller is moved positively back and forth in the arc 80 of a circle by the arm of the rocking bar or shaft by which it is carried, and is yieldingly pressed against the fabric by the spring-rod on which it is journaled, so that it creases the cloth with a yielding rolling pressure, which 85 precludes the possibility of cutting or abrading the thinnest fabrics.

The bracket F, by which the creaser is connected to the attachment-bar, is on the front side of the creaser, and the creasing-lip is below 90 the center of movement of the rocking bar, so that the creasing devices are not only rearward of the needle, but are rearward of the presser-foot of the machine, as clearly shown in Fig. 1. From this construction and 95 arrangement of parts I am enabled to form well-defined creases nearer to the line of stitches than can be made by the creasers heretofore in use, for the reason that if a crease be made in front of the presser-foot and 100 near enough to the needle to come in the line of the presser-foot it will be partly obliterated when passed under the said foot in the operation of sewing, and where the creasing devices are opposite to the presser-foot the latter will prevent them from being adjusted as 105 closely to the line of stitches as is necessary in making very narrow tucks.

As I believe that I am the first to construct a tuck creaser or marker in such a manner 110 that the creasing devices are rearward of the presser-foot of the machine, and also the first to provide a tuck creaser or marker with a rocking bar or shaft having an arm which carries a creasing-roller back and forth positively 115 in the arc of a circle while it is held in yielding contact with a knife-edge or creasing-lip beneath the center of motion of the said bar or shaft, I do not wish to be understood as limiting my invention to the details of construction herein shown, as various modifications of my invention may be made without departing from the spirit thereof.

The attachment and presser-foot holding devices incidentally shown in Fig. 1 are not 120 herein claimed, as they are embraced by my application hereinbefore referred to.

I claim—

1. The combination, with the operative parts of a sewing-machine, of a tuck creaser or 125 marker the creasing or marking devices of which are rearward of the presser-foot of the machine.

2. In a tuck creaser or marker for sewing-

machines, the combination, with a rocking bar or shaft having a rigid arm carrying a spring-pressed creasing-roller which is oscillated in the arc of a circle directly by the said arm, of 5 a creasing-lip to co-operate with the said roller, and against which lip the said roller is yieldingly pressed as it is moved back and forth over the same, said creasing-lip being below the center of movement of the said bar 10 or shaft, so that the said roller is caused to travel positively back and forth over the said lip in the direction of movement of the said bar or shaft as the latter is oscillated.

3. In a tuck creaser or marker for sewing- 15 machines, the combination of a rocking bar or shaft extending lengthwise of the marker, and provided with a rigid depending arm having a slot near its lower end, a spring-rod passing through said slot, a creasing-roller 20 journaled on said rod within a recess at the lower end of said arm, and a creasing-lip to co-operate with said roller.

4. The combination, with the bar E, having the flattened lower portion, e, provided with 25 the creasing-lip e', of the rocking bar or shaft G, journaled on the said bar E, and having two depending arms, g and g', a spring-rod attached to the said arm g' and extending through a slot in the arm g, a creasing-roller 30 journaled on the said spring-rod, and an operating-lever for the bar G.

5. The combination, with the bar E, having the flattened lower portion, e, provided with the creasing-lip e', of the rocking bar or shaft G, journaled on the said bar E, and having a 35 depending arm carrying a creasing-roller, and an operating-lever pivoted on the said bar E, and having a portion notched to embrace and thus operate the said bar G.

6. The combination, with the bar E and the 40 creasing devices supported thereby, of the bracket F, having ears f, through which the said bar extends, a guide-carrying rod also extending through the ears of the said bracket, a block interposed between said rod and bar, 45 a clamping-loop surrounding said rod, bar, and block and provided with a threaded stem, and a set-nut on the said stem.

7. The combination, with the bar E and the 50 creasing devices supported thereby, of the bracket F, having the perforated ears f, the rod j, the block m, interposed between said bar and rod, the loop having a threaded stem, a set-nut on said stem, and the cap or housing plate n.

In testimony whereof I affix my signature in presence of two witnesses.

JOHN M. GRIEST.
